UNITED STATES PATENT OFFICE.

FAY H. MARTIN, OF HYDEPARK, MASSACHUSETTS, ASSIGNOR TO TEXTILE MACHINERY COMPANY, OF BOSTON, MASSACHUSETTS, A CORPORATION OF MAINE.

FLIER.

SPECIFICATION forming part of Letters Patent No. 711,907, dated October 21, 1902.

Application filed May 9, 1902. Serial No. 106,609. (No model.)

To all whom it may concern:

Be it known that I, FAY H. MARTIN, a citizen of the United States, residing at Hyde-park, in the county of Norfolk, State of Massachusetts, have invented a certain new and useful Improvement in Fliers, of which the following is a specification, reference being had therein to the accompanying drawings.

My invention has relation more especially to the pressers of fliers for roving-machines and the like and to the means and manner of combining the said pressers with the presser-carrying arms of the fliers.

The invention consists in the novel and improved construction and arrangement which I will now proceed to describe, with reference to the accompanying drawings.

In the drawings, Figure 1 is a view in elevation showing a spindle, bobbin, and flier having my invention applied to the latter. Fig. 2 is a view in transverse section on line 2 2 of Fig. 1. Figs. 3 to 6 are views like Fig. 2, showing modifications. Fig. 7 is a partial side elevation showing a modification. Figs. 8 and 9 show different forms of presser-fingers.

Having reference to the drawings, 1 designates the spindle of a roving-frame; 2, a bobbin surrounding the same; 3, a flier applied to the said spindle; 4, the balancing-arm of the flier; 5, the arm to which the presser-finger is connected, and 6 the boss or nose of the flier.

7 is the presser-finger.

In accordance with my invention the presser-finger 7 is mounted so as to cause it to swing or turn about a center of motion which is located, as indicated at x , Fig. 1, at a point in the neighborhood of the upper end of the bobbin and also midway or approximately midway radially of the spindle and bobbin, between the periphery of the empty bobbin and that of a full load of roving wound upon the said bobbin. The presser-finger 7 cannot be actually pivoted at the point x aforesaid midway between the periphery of the empty bobbin and that of a full load of roving, because this would interfere with the winding of roving upon the bobbin; but I secure the same result, in effect, by connect-

ing the presser-finger with the carrying-arm 5 therefor pertaining to the flier in a manner which causes the presser-finger to turn or swing about the said point.

The drawings show different ways of carrying the invention into effect. Usually I provide the arm 5 of the flier with a box or tubular guide 51; Figs. 1 and 2, within which a portion 71 of the length of the presser-finger 7 is received. The said box or guide 51 and said portion 71 of the presser-finger are fitted to each other. The said portion 71 is capable of moving endwise through the box or guide 51, and the two are combined in a manner which prevents the presser-finger 65 from turning around its longitudinal axis. Usually I form the portion of the presser-finger which fits within the said box or guide rectangular in cross-section, the interior of the box or guide being shaped accordingly, 70 although this particular shape in cross-section is not in all cases essential. Other known means may be adopted in some instances, if preferred, for the purpose of preventing the presser-finger from turning around its longitudinal axis. In many instances, indeed, special provisions for preventing the presser-finger from turning around its longitudinal axis are not absolutely required, inasmuch as the arc shape of this portion 71 of the presser-finger 75 and of the box or guide 51 will itself prevent the turning movement. I further form this portion 71 of the presser-finger 7 with a curvature, such as is shown in the drawings, the said portion 71 being curved on the arc of a 80 circle of which the center is located at the point x , Fig. 1. As already stated herein, the said point x is located midway or approximately midway between the periphery of the empty bobbin and the periphery of a full load 90 of roving, the distance being measured radially of the spindle and bobbin. The curvature of the box or guide is struck from the same center. Consequently when force is applied to the presser-finger tending to move it 95 it slides through the box or guide 51 in the direction of its length, its movement with reference to the aforesaid center of motion causing the shoe 72 at the lower extremity of the presser-finger to move toward or from the 100

longitudinal axis of the spindle and bobbin along an arc of which the center is the center of motion α aforesaid and of which the radius is the line extending from the center 5 of motion α to the shoe 72. The presser-finger is made comparatively long, and thereby sufficient length of radius is secured to render the arc of movement of the shoe 72 a comparatively flat one. Therefore although the 10 shoe 72 moves in an arc the departure of its path of movement from a straight radial line is not sufficiently great to manifest itself by occasioning any noticeable irregularity in the positioning of the ends of the successive layers of roving upon the bobbin, and, moreover, when the load of roving is full the shoe 72 occupies a position on the same radial line as at the time of beginning to wind on the empty 15 bobbin.

20 A single or continuous arc-shaped box or guide 51 may be employed, as in Fig. 1, or the portion 71 of the presser-finger may be fitted to two or more sections 52 52, as in Fig. 7. The presser-finger may be shaped as in 25 Fig. 8, with shoulders 53 53 at opposite ends of the curved portion 71 to limit the extent of the swinging movement of the presser-finger by making contact with the opposite ends of the guide or guides. In Fig. 9 the upwardly-projecting weight-arm 73 projects from near the middle of the convex side of the arc-shaped portion 71 of the presser-finger and plays between the two box or guide sections 52 52 of Fig. 7, the limits of the movement of the presser-finger being determined 30 by contact of the said weight-arm with the opposite sections 52 52.

The box or guide 51 usually will be formed with one side thereof separate from the remainder and secured in place after the presser-finger has been applied to the box or guide. In Fig. 3 the separate cover-piece 54 is shown received in rabbets that are formed in the opposite sides of the box or guide and is 35 supposed to be secured by soldering or brazing. In Fig. 2 the cover-piece (here designated 55) is fitted to the opposite sides of the box or guide 51 with dovetailed joints, and after having been pushed into place it is there held 40 by peening along the said joints, clamping thereby the edges of the said cover-piece. In Fig. 4 the cover-piece 56 is simply soldered or brazed upon the outer edges of the opposite sides of the body of the box or guide, 45 while in Fig. 5 the said cover-piece 57 is similarly secured, but is formed with side flanges 571 571, which embrace the opposite sides of

the said body. In Fig. 6 the construction is reversed in this that the side 58 is first attached to the flier-arm 5, while after the 60 presser-finger and the body 59 of the box or guide have been fitted together the edges of the said body are applied and secured to the said side 58.

Various other changes in form and construction are possible to be made without involving a departure from the broad principles of my invention.

I claim as my invention—

1. A flier provided with a presser-finger 70 mounted and operating to swing or turn in a radial plane about a center of movement located adjacent the head of the bobbin in connection with which the said flier cooperates in practice, and at a point intermediate the 75 periphery of the empty bobbin and the periphery of the full load.

2. A flier provided with a presser-finger mounted and operating to swing or turn in a radial plane about a center of movement located adjacent the head of the bobbin in connection with which the said flier cooperates in practice, and at a point midway between the periphery of the empty bobbin and the periphery of the full load.

3. A flier provided with a presser-finger 85 mounted on one of the arms thereof and provided with a curved or arc-shaped guide permitting movement of the presser-finger in operation about a center located adjacent the head of the bobbin in connection with which the flier is used, and intermediate the periphery of the empty bobbin and the periphery of the full load.

4. A flier provided with the arc-shaped box 90 or guide, and having the presser-finger formed with the curved portion fitting the said box or guide and movable therein about a center located adjacent the head of the bobbin in connection with which the flier is used.

5. A flier provided with the arc-shaped box 95 or guide, and having the presser-finger formed with the curved portion fitting the said box or guide and movable therein about a center located adjacent the head of the bobbin in 100 connection with which the flier is used, and intermediate the periphery of the empty bobbin and the full load.

In testimony whereof I affix my signature in presence of two witnesses.

FAY H. MARTIN.
